I. SCHMIDT,
BURIAL CASKET.

APPLICATION FILED SEPT. 22, 1915.

1,171,069.

Patented Feb. 8, 1916.

IDA SCHMIDT

By *Watson E. Coleman*

Attorney

UNITED STATES PATENT OFFICE.

IDA SCHMIDT, OF LOS ANGELES, CALIFORNIA.

BURIAL-CASKET.

1,171,069.

Specification of Letters Patent. Patented Feb. 8, 1916.

Application filed September 22, 1915. Serial No. 52,031.

To all whom it may concern:

Be it known that I, IDA SCHMIDT, a citizen of the United States, residing at Los Angeles, in the county of Los Angeles and State of California, have invented certain new and useful Improvements in Burial-Caskets, of which the following is a specification, reference being had to the accompanying drawings.

10 My invention relates to burial caskets, and particularly to caskets made of a plurality of sheets of metal, and the general object of my invention is to provide a metallic casket, the cover or lid of which is 15 so constructed that a sliding member may be supported in sliding engagement with the cover or lid so as to be extended across an opening in the lid or cover or pushed back to disclose said opening and when in 20 the latter position is entirely concealed, and further to provide means whereby this sliding member may be held in either of its positions.

Other objects will appear in the course of 25 the following description.

My invention is illustrated in the accompanying drawings, wherein:

Figure 1 is a plan view partly broken away; Fig. 2 is a longitudinal sectional view; Fig. 3 is an enlarged sectional view showing the manner in which the body of 30 the casket is made up of laminated sheets.

Referring to these figures, 2 designates 35 the body of a casket, and 3 the cover or lid thereof, the cover or lid being coterminous with the body of the casket. Both the cover and lid of the body of the casket are formed of laminated sheets of material. The material used may be copper, lead, steel, galvanized iron, aluminum, or any other material 40 which may be suitable for the purpose, these sheets of material which are designated *a* being separated from each other by spaces filled with any suitable filling material designated *b*. This filling material may be magnesite, compressed paper, cork, wood, asbestos, cement, or any other filler which will be relatively light and which 45 will have the necessary strength. The sheets of material may be held together in any suitable manner, as by screws, rivets, bolts, etc., and the outer and inner sheets of material are to be coated with any desired metal alloy or enamel, this coating or layer 50 of alloy or enamel being designated *c*. This outside coating may be of any thickness,

white, dark, or any other desired shade of color, and may be also made to imitate wood of various characters.

The body 2 is formed along its upper edge 60 with the edge face 4 and the cover 3 is formed along its margin with the outwardly extending flange 5 which will confront the face 4, and with the downwardly extending flange 6 which may be inserted within the 65 body and fit tightly therein. Bolts 7, screws, or other suitable fastening devices may be used to engage the flanges 4 and 5 so as to hold the cover firmly in place. The cover is formed with an opening 8 at its head 70 end which may be of any suitable extent and designed to be protected by a slide formed of a sheet of glass 9. One wall of the opening 8 is preferably so formed as to provide the slide receiving recess 10 75 within which the glass slides. The glass is held in place by means of a facing strip 11. This glass 9 is in turn protected by a lid 12 which extends over the opening in 80 the cover and is bolted to the cover or otherwise attached thereto in any suitable manner.

It will be noted that by forming the cover of the casket of laminated sheets it is 85 relatively easy to provide the lateral grooves into which the slide or pane 9 is adapted to be supported and moved and to form the recess 10 within which the slide 9 is concealed when the pane is pushed back. All 90 of the sheets of material are cut through to form the opening 8. The opening in the intermediate sheets, however, is made slightly larger so as to provide the lateral grooves for the slide and also to provide the recess 10 within which the slide is received. The facing strip 11 is disposed within a transverse recess 11^a formed adjacent that 95 end of the opening 8 toward the foot of the casket, this transverse recess intersecting the recess 10. Thus by removing the facing strip 11 is disposed within a transverse recess 11^a formed adjacent that end of the opening 8 toward the foot of the casket, this transverse recess intersecting the recess 10. Thus by removing the facing strip 11 the slide may be shifted either to 100 close the opening 8 or uncover the opening 8 and then the slide may be held in place in either of its adjusted positions by inserting the facing strip 11 in its recess 11^a.

The casket is to be cushioned with excelsior, cotton, silks, or any other material which may be desired, and the casket is also provided with handles fastened in any suitable manner to the body of the casket. It is to be understood, of course, that any material or combination of material may be 110

used to form the laminated sheets of which the casket is made.

Having thus described my invention, what I claim is:

- 5 1. A casket cover composed of a plurality of metallic sheets, the cover being cut away at one end to provide an opening and formed with a recess extending from one end of the opening, the cover being also formed with a transverse recess extending from the upper surface of the cover adjacent the end of the opening and a slide mounted within the recess and movable into a position across the opening, and a facing strip removably disposed in the transverse recess and adapted to hold the slide either in place across the opening or in place within the recess.
- 10 2. A casket cover composed of a plurality of metallic sheets, all of the sheets being cut away at one end of the cover to provide an opening, the intermediate sheets being
- 15

Copies of this patent may be obtained for five cents each, by addressing the "Commissioner of Patents, Washington, D. C."

cut away to a greater extent than the outer and inner sheets to provide lateral slide supporting grooves and a slide receiving recess forming a continuation of the opening, the cover being formed with a transverse recess extending downward from the upper surface of the cover and intersecting said first named recess, a slide disposed in the first named recess, slidable in said grooves from an open to a closed position, and a facing strip removably disposed in the transverse recess to thereby hold the slide either in place across the opening or within said first named recess.

In testimony whereof I hereunto affix my signature in the presence of two witnesses.

IDA SCHMIDT.

Witnesses:

ALMA BENNETT,
MAY SCHMIDT.
